UNITED STATES PATENT OFFICE.

JAMES C. COVERT, OF WATERVLIET, NEW YORK.

DESIGN FOR A SNAP-HOOK MEMBER.

SPECIFICATION forming part of Design No. 32,193, dated February 6, 1900.

Application filed December 19, 1899, Serial No. 740,948. Term of patent 14 years.

To all whom it may concern:

Be it known that I, JAMES C. COVERT, a citizen of the United States, residing at Watervliet, in the county of Albany and State of New York, have invented and produced a new and original Design for a Snap-Hook Member; and I do hereby declare the following to be a full, clear, and exact description of the same, reference being had to the accompanying drawings, forming a part thereof.

This invention relates to a new and original design for a snap-hook member, and it is embodied in the peculiar form, shape, and configuration presently to be described, and shown in the accompanying drawings.

In the drawings the design is shown in elevation in Figure 1. Fig. 2 is an edge view.

The hook portion proper has a tongue or point *a* and a flat-sided shank *b*, which latter has a substantially straight inner edge.

The rear or, as shown, lower portion of the hook is carried outward and upward and is formed with a curved edge.

c is a depression in the outwardly and upwardly extending portion of the shank. 25

The back of the hook is slightly curved.

The essential feature of the design is the hook member, substantially as shown and described.

Having thus described the invention, what I claim as new, and desire to secure by Letters Patent, is—

The design for a snap-hook member, substantially as shown and described.

In testimony whereof I affix my signature in presence of two witnesses.

JAMES C. COVERT.
